United States Patent Office

Des. 177,558
Patented May 1, 1956

177,558

PORTABLE ELECTRIC HAND SAW

Francis D. Dolan, Toledo, Ohio, assignor to The American Floor Surfacing Machine Company, Toledo, Ohio, a corporation of Ohio

Application May 17, 1955, Serial No. 36,036

Term of patent 14 years

(Cl. D93—3)

FIG. 1.

FIG. 2.

FIG. 3.

FIG. 4.

FIG. 5.

Fig. 1 is a top plan view of a portable electric hand saw showing my new design;

Figs. 2 and 5 are opposite reduced end views thereof, and

Figs. 3 and 4 are reduced front and rear side views, respectively, thereof.

I claim:

The ornamental design for a portable electric hand saw, substantially as shown.
